GRINDING MACHINE

Robert Daniel Heffelfinger, Reading, Pa., assignor
to Hamilton Watch Company, Lancaster, Pa.

Application September 4, 1941, Serial No. 409,499

11 Claims.

(Cl. 51-48)

This invention relates to grinding machines and has for an object the provision of improved means and method of grinding.

Another object is to provide means and method of grinding jewels to a high degree of accuracy.

Another object is to provide a jewel grinding machine of the centerless grinder type in which the grinding wheel is adapted to be oscillated along its own axis.

Another object is to provide a jewel grinding machine of the centerless grinder type having improved jewel supporting means.

Another object is to provide a jewel grinding machine of the centerless grinder type, having accurate and micrometrically measurable adjustment and action.

Another object is to provide a grinding machine having means adapted to resurface the grinding wheel to a micrometrically controlled depth and means adapted to advance the object to be ground a micrometrically controlled amount in accordance with the depth of the resurfacing of the wheel.

Another object is to provide a jewel grinding machine adapted to interchangeably mount a holder for rough grinding and a holder for fine grinding.

Other objects and advantages of the invention will become apparent from the following description taken in connection with the accompanying drawings. It will be apparent that many changes may be made in the details of construction, arrangement of parts and method shown and described without departing from the spirit of the invention as expressed in the accompanying claims. I, therefore, do not wish to be limited to the exact details of construction, arrangement of parts and method shown, as the preferred form only has been shown by way of illustration.

Referring to the drawings:

Fig. I is a plan view of the device embodying the invention;

Fig. II is an enlarged, partial front elevation of the structure of Fig. I, illustrating the grinding wheel oscillating mechanism, taken on line II of Fig. I.

Fig. III is an illustration of the position of the workpiece and its support in the device.

Fig. IV is a front elevation of the device.

Fig. V is a right end elevation of the structure of Fig. IV;

Fig. VI is a left end elevation of the structure of Fig. IV;

Fig. VII is a partial enlargement of Fig. V, showing the work support;

Fig. VIII is a partial enlargement of Fig. VI, showing the regulating roller support;

Fig. IX is a partial front elevation of Fig. VII, showing the support for solid workpieces;

Fig. X is a front elevation similar to Fig. IX, showing the support for drilled workpieces;

Fig. XI is a partial right end elevation of the structure of Fig. X;

Fig. XII is a detail of the wire holding portion of the structure of Fig. X; and

Fig. XIII is a detail of the wire tightening portion of the structure of Fig. X.

This invention relates to improved means and method of grinding the peripheries of objects to circular contours and/or grinding the peripheries in concentricity with given centers in the objects.

The device and method of this invention may be utilized for the grinding of any type of object desiring a peripheral grinding and may readily be used to grind to an approximation or to very close tolerances.

In the formation of objects expensive to purchase and/or process, for instance watch jewels,

it is desirable in order to meet the exacting re-

quirements of modern watchmaking to form the periphery as a circle which, in the case of solid

jewels, needs to be formed with as little waste of

jewel material as possible, and in the case of

drilled jewels, accurately concentric with the

drilled hole. In the past, solid jewels have been

ground without the careful regard to minimum

stock loss that should be exercised and drilled

jewels have been ground without careful regard

to the achievement of concentricity of the periph-

ery with the drilled hole.

This invention provides means and method of

permitting the peripheral grinding of objects such

as solid watch jewels, to accurate circular con-

tours with a minimum of waste material and of

objects such as drilled watch jewels, not only with

a minimum of waste material, but also to an ac-

cute concentricity with the drilled hole.

In general, it utilizes a grinder of the centerless

type with means for supporting the jewels in po-

sition against the grinding wheel in addition to

the holding action of the regulating roller, with

means for oscillating the grinding wheel on its

own axis and micrometric adjustments to insure

accuracy of adjustment and operation.

The device embodying this invention includes,

as shown in Fig. I, a grinding wheel 1 mounted

for rotation about its axial shaft 2, and a regu-

lating roller 3 mounted at one end for rotation

about its axial shaft 4.

When the device is operating with its parts in

proper adjustment, the grinding wheel 1 oscillates

about its axis, and the regulating roller 3 oscillates

about its axis, the amplitude of oscillation of the

regulating roller 3 being greater than the amplitude

of oscillation of the grinding wheel 1, so that the

regulating roller 3 oscillates in a circle concentric

with the grinding wheel 1, and the grinding wheel 1

oscillates in a circle concentric with the regulating

roller 3.

proper grinding position, the shafts 2 and 4 are substantially parallel, and the peripheries of the grinding wheel 1 and regulating roller 3 roll on or closely adjacent each other.

The grinding wheel 1 is driven through the pulley 5, and the regulating roller 3 through either pulley 6 or pulley 7, depending on the speed desired, and both are preferably rotated in a clockwise direction from the left end elevation view as shown in Fig. VI.

Thus, as illustrated in Fig. III, the peripheries of the grinding wheel 1 and regulating roller 3 pass each other going in different directions. These directions may be reversed if desired, but one should be opposite the other at the passing point in order to cause the workpiece, which is a watch jewel 8 in this instance, and mounted between the grinding wheel 1 and the regulating roller 3, and held from below by supporting plate 9, to rotate so as to be uniformly and properly abraded.

Watch jewels, in the stage of their manufacture at which the process of peripheral grinding is used, are substantially flat discs and the operation desired is, in the case of an undrilled jewel, to grind the disc into a peripherally circular shape, and in the case of the drilled jewel, not only into a circular shape but also with the periphery concentric with the drilled hole.

The work involved in grinding the peripheries of such jewels is extremely delicate. Approximate dimensions for a jewel may be 15 thousandths of an inch in thickness, 30 thousandths in diameter, and when drilled, the hole may be 5 thousandths in diameter. In order to meet the rigid present day requirements of quality watchmaking, the machine of this invention has been designed to grind a jewel to size with a plus or minus tolerance of only one-half of one-tenth of a thousandth of an inch.

The illustrated centerless grinder type of machine is used, with the solid jewels held between the grinding wheel 1 and the guide roller 3 by the pressure of the guide roller 3 on them, a supporting plate 9 beneath them, and the action of a spring pressed pin 10 (see Fig. IX) on the jewels in end to end relation and against an upright 11 on the supporting plate 9. Drilled jewels are held in grinding position as illustrated in Fig. X. In addition to the customary pressure of the regulating roller 3, they are strung on a wire 11 and held in end to end relation by end pressures of the wire holders, and also supported from beneath by a plate 12, similar in function and form to plate 9 of Fig. IX.

The machine of this invention is so made as to permit interchange of jewel holding assemblies. When solid jewels are being ground, or a rough grind on a drilled jewel is being carried out, the assembly of Fig. IX is used, and when the drilled jewel is being fine ground to bring its periphery to concentricity with its hole, the assembly of Fig. X is used.

Movements of the regulating roller and the jewel holders with respect to the grinding wheel, as well as the adjustment of the grinding wheel dresser, are made micrometrically in this device and this contributes largely to the close tolerances within which this machine may operate.

The objects of this invention have been accomplished by providing the several parts of the machine with variety and delicacy of movement and adjustment, with the movements and adjustments cooperatively functioning to provide unique sup-

port of the jewels being ground and an effective method of grinding.

It is preferable to grind the jewels in a group, with the jewels laid end to end across the face of the grinding wheel, which is oscillated on its own axis so as to utilize the entire lateral extent of the periphery of the wheel in grinding the jewels, and to wear the wheel down with relative uniformity throughout.

10 The jewels may be ground singly or in small groups if desired, but it is easier to achieve the great accuracy demanded by using enough jewels, end to end, to approach the dimension of the width of the periphery of the grinding wheel. The jewels are grouped in end to end relation and held together by a suitable adhesive such as water repelling grease, so that they form, in effect, a single long substantially cylindrical object which is much more amenable to accurate processing than a single jewel or smaller group would be.

The first step in grinding the jewels is to make certain that the grinding wheel presents a uniform peripheral surface. This is done by operating the grinding wheel dresser. The dresser comprises a threaded shaft 13 which is mounted in brackets 14 and 15 in parallelism with the axis shaft 2 of the grinding wheel 1. The shaft 13 is rotatable in its mounting but is fixed against longitudinal movement.

25 An extension 16 of bracket 15 supports a handle 17 which is so connected to the shaft 13 adjacent its support in bracket 15 that turning of the handle 17 rotates the threaded shaft 13.

The dressing tool 18 is carried across the peripheral face of the grinding wheel 1 by a rider block 19. This block is internally threaded and mounted on shaft 13. The block 19 is held against rotation about and is free to travel along the shaft 13 so that rotation of the shaft 13 through turning of the handle 17, causes the rider block 19 to move along the shaft 13 and carry the tool 18 across the face of the grinding wheel 1.

30 The rider block 19 is mounted on a support 19a which is in dovetail sliding arrangement with a rigid support 20 so that the movement of the tool 18 across the grinding wheel is firm and regular.

The depth to which the grinding wheel is dressed may be regulated within close limits through the use of the micrometer screw 21. 35 Screw 21 is connected to the dressing tool 18 and is adapted to move the tool toward or away from the periphery of the grinding wheel in a direction normal to the direction of movement of the rider block 19 along the shaft 13. The tool 18 is held 40 rigidly in the position of depth to which it has been moved by the locking action of lock member 22 on the micrometer screw 21.

The above described micrometer measurement of the depth of the grinding wheel dressing action 45 is an important feature of this invention since it provides a basis for very accurate compensation of the position of the jewels with relation to the grinding wheel. When such close tolerances of the jewels as have been mentioned are involved, it is essential to know the extent of and to be 50 able to accurately compensate for, any change in the dimensions of the grinding wheel.

55 During the grinding operation, the grinding wheel is oscillated on its own axis so as to utilize the entire width of the periphery of the wheel and thus cause the wheel wear to be uniform throughout its width. The grinding wheel supporting shaft 2 is mounted in bearings 23 and 24 and so formed and mounted as to be slidable in 60 the bearings 23 and 24 along its longitudinal axis,

thus permitting lateral movement or oscillation of the grinding wheel 1.

The arrangement of automatic means for oscillating the grinding wheel is illustrated in Fig. II. The wheel supporting shaft 2, mounted in bearing 23, has a peripherally recessed collar 25 mounted thereon and it is through the action of pin member 26 mounted on cam lever 27 and extending into the recess of the collar 25, that the shaft 2 is moved so as to oscillate the grinding wheel.

The cam lever 27 is pivoted on the body of the machine at 28 and has a cam following nose 29 which is constantly urged against the oscillator cam 30 by spring member 31, mounted in a recess in the body of the machine. The contour of cam 30 is such that when the cam is rotated, the cam lever 27 is made to move about its pivot 28, and the shaft 2 is moved back and forth along its own longitudinal axis.

When the grinding wheel is being dressed, it is necessary to stop its oscillation so that the dressing may be accurate and accomplished without unnecessary danger of breaking the dressing tool. A locking member 32 is provided for this purpose. It is pivoted at 33 and movable about that pivot through the use of its handle 34 so as to contact the cam lever 27 and push it away from the cam 30 against the action of the spring 31.

The cam 30 is driven through a train of gears from the grinding wheel shaft 2. This train consists of a gear 35 mounted on the shaft 2, an intermediate gear 36, a worm gear 37 and the cam gear 38. This gear train is so formed as to oscillate the grinding wheel out of step with its rotation so as to achieve maximum distribution of the wear on the grinding wheel.

The supporting unit for the regulating roller 3 is shown in assembly in Fig. IV and enlarged in Fig. VIII. In Fig. IV it is shown as the unit at the left of the machine. In order to provide adjustment of the roller 3 laterally of the grinding wheel periphery, the unit is mounted for lateral adjustment on the base plate 39. An intermediate plate 40 has a T slot 41 in which a headed holding bolt 42 is positioned. A camming lock bolt 43 is mounted in the base 39 and is designed to draw the bolt 42 downward and lock the intermediate plate 40 to the base 39 with the roller 3 in adjusted lateral position along the track 44.

The entire regulating roller unit is readily removable from the machine through the connection of the locking bolt 42 between the base plate 39 and the intermediate plate 40.

The axis 4 of the regulating roller 3 must be parallel to the axis 2 of the grinding wheel 1 and the peripheral grinding surface thereof in order to grind the jewels to equal diameters. It is the function of the wheel dresser to produce parallelism between the grinding wheel axis and periphery. Accordingly the regulating roller unit is pivoted about a vertical pivot 45 located to one side of the regulating roller 3, so that the roller may be bodily moved in a horizontal arc toward and away from the grinding wheel, and its axis 4 brought into parallelism with the axis 2 of the grinding wheel 1.

The pivot 45 extends through the pivot plate 46 and is secured in the intermediate plate 40. The intermediate plate 40 is provided with a horizontally extending slot 47, through which extends a lock bolt 48, secured to the pivot plate 46. The lock bolt 48 is loosened to permit the regulating roller unit to be moved about its vertical pivot 45.

45, and thereafter is tightened to hold the unit in its arcuately adjusted position.

The regulating roller 3 is movable away from the grinding wheel 1 in a straight line horizontal movement in order to facilitate the loading or unloading of the jewels, and to make the grinding portion of the machine accessible.

The straight line horizontal movement of the regulating roller with respect to the grinding wheel is provided for by the arrangement of the sliding plate 49 which is mounted in a dovetail track on the pivot plate 46, and the movement is accomplished through the manual operation of the handle 50.

15 The slide plate 49 is micrometrically adjustable on the pivot plate 46 through the action of adjustment screw 51 and indicator finger 52. The inner end of the adjustment screw 51 butts against the pivot plate 46 to limit the movement of the slide table 49 towards the grinding wheel. The adjustment screw 51 is locked in adjusted position by the lock nut 53.

Movement of the handle 50 downward will move the regulating roller 3 away from the grinding wheel 1 since the handle 50 is pivoted on the sliding plate 49 at 51 and pivotally joined with a link 52 which is pivoted at 53 to the pivot plate 46.

25 That part of the supporting structure of the regulating roller unit which is immediately adjacent and supporting the regulating roller 3 is mounted on a horizontal pivot 54 which is bracketed to the slide plate 49 and parallel to the axis 4 of the regulating roller. Consequently the regulating roller 3 is movable about pivot 54 toward and away from the grinding wheel 1. The bracket support of the pivot 54 has a stop shoulder 55 which a stop pin 56 mounted in the pivoted regulating roller support is adapted to abut to limit the movement of the regulating roller 3 toward the grinding wheel about the pivot 54.

35 The regulating roller 3 is constantly urged toward the grinding wheel 1 by a weight 60 (Fig. VI). The weight 60 operates through a flexible connector 62a of rope or other suitable material, connected to the regulating roller unit at 62 above the pivot 54. Consequently the weight 60 holds the stop pin 56 against the shoulder 55 and the adjustment screw 51 against the outer end of the pivot plate 46.

40 The regulating roller 3 preferably has an outer surface in the form of a sleeve of cushioning material such as rubber, to permit the rotation of irregular jewels between the grinding wheel and the regulating roller. Minor irregularities are taken up by the irregularities sinking into the outer cushion of the regulating roller.

45 More pronounced irregularities cause the regulating roller to be bodily moved about the pivot 54, while extreme irregularities would cause the regulating roller to be moved about the pivot 54 until stopped by the micrometrically adjustable screw 51, after which the motion would transfer to the slide table 49 and any further motion away from the grinding wheel would be rectilinear.

The screw 51 is bracketed to the slide plate 49 and its threaded end is adapted to contact the regulating roller supporting structure which is pivoted about the pivot 54. The limit of the movement of the regulating roller 3 about the pivot 54 away from the grinding wheel may, therefore, be set micrometrically by regulation of the adjustment screw 51 which is locked in adjusted position by a lock nut 51a. In this manner a limit may be set to the relatively easy movement of the regulating roller 3 away from

the grinding wheel 1 about the pivot 54. When this limit has been reached, a greater load is imposed upon further movement away from the grinding wheel by making it necessary to move the slide table 46 in addition. Both the pivoted and sliding movements are under the influence of the weight 60.

The arrangement of the cushioning surface of the regulating roller for minor jewel contour irregularities, movement about the pivot 54 for greater irregularities and the extra movement of the slide table 49 for exceptional irregularities and the adjustability of the arrangement all provide useful means for taking care of contour irregularities in the jewels without damage to the jewels or the machine.

The regulating roller 3 is also movable about the pivot 54 by manual use of the handle 63. This is used when access to the jewels is desired without the necessity of the movement of the slide table 49.

The regulating roller 3 is also adjustable vertically with respect to the grinding wheel. This is accomplished through the sliding relation of the immediate support of the regulating roller with that portion of the unit which is pivoted at 54. The vertical movement is carried out by manipulation of the micrometer adjustment screw 64. The screw 64 is bracketed to the immediate support of the regulating roller and threaded into that part of the unit which is pivoted at 54.

A spring member 65 acts to urge the regulating roller shaft 4 upwardly to take up for whatever slack may be introduced by irregularities in the thread of the adjustment screw 64. The regulating roller is locked in its vertically adjusted position by a lock member 66 which draws the immediate support of the roller against that part of the unit which is pivoted at 54.

All of the adjustments and movements described above in connection with the regulating roller provide for very accurate placement of the regulating roller 3 with respect to the grinding wheel 1 and the jewels 8. These accurate and fine movements and adjustments contribute largely to the achievement of the hitherto unobtainable accuracy and close tolerance processing of jewels which are the results of this invention.

The jewels dealt with particularly are rubies of the type used in watches.

The jewel supporting structures shown in Figs. IX and X are interchangeable and used separately. Figs. IX and VII show one structure and Figs. X and XI show another. They are both mountable on the general structure as shown in Fig. IV as the unit at the right of the machine, although the unit there shown is the unit of Fig. IX.

Both of these structures are adjustably and removably secured to the base plate 39 by means of a T slot and headed bolt as shown at 67 and 68 respectively in Fig. V, in just the same manner and for the same purposes as the slot 41 and bolt 42 described in connection with the structure of Fig. VIII.

They also have an intermediate plate 69 and a pivot plate 70 with a pivot 71, adjustment slot and screw 72 and 73 and a slide plate 74 with micrometer screw 75, similar to the structures described in connection with Fig. VIII. The jewel supports are accordingly laterally adjustable, removable, micrometrically adjustable toward and away from the grinding wheel, and pivotable about a vertical pivot to dispose the end to end assembly of jewels in parallelism with the axis

and peripheral grinding edge of the grinding wheel.

The jewel supporting structure which is adapted to support solid jewels both for rough and fine grinding, and drilled jewels for rough grinding, is illustrated in Figs. VII and IX.

The operation of the slide tables 74 of the jewel supporting units differs from the operation of the slide table 49 of the regulating roller supporting unit in that the tables 74 are not constantly urged toward the grinding wheel but are adjusted to the desired position and then locked in place. In Fig. VII this is accomplished by the lock member 76, and in Fig. XI by the lock bolt 74a. The screw 75 may be locked in adjusted position by lock 77. Consequently the jewels are positioned against the grinding wheel by adjustment and then rolled thereagainst under pressure by the regulating roller 3 and in accordance with the rotation thereof.

The jewel support of Fig. VII is pivoted about a horizontal pivot 78 which in position of operation extends in a direction normal to that of the axis 2 of the grinding wheel 1. This arrangement permits the aligned group of jewels which are to lie between the pin 10 and abutment 10a (Fig. IX) to be adjusted with respect to levelness so as to make possible the desired grinding action throughout the jewel group. In order to achieve uniform grinding action throughout, the jewel group must be level and parallel to the axis and periphery of the grinding wheel.

The pivot 78 is threaded into the vertical pivot plate 79 and extends as a pivot through the upright 80 which is fixed to the horizontal slide plate 74. A lock bolt 81 operable in conjunction with the pivot 78 is also threaded in the vertical pivot plate 79 and movable horizontally in a slot 82, about the pivot 78 as a center, in the fixed upright 80 as the vertical pivot plate 79 is moved about the pivot 78, and is adapted to lock the plate 79 in adjusted pivoted position.

The jewel holding unit of Figs. VII and IX includes the jewel end support plunger 83 and the support plate 8. Plunger 83 and plate 8 are movable vertically as a unit with respect to the remainder of the support assembly through a vertical slide plate 84 mounted in a dovetail slide in pivot plate 79. Support plate 8 and the auxiliary slide plate 85 which holds the jewel plunger 83 are both mounted on slide plate 84 and consequently are together vertically micrometrically adjustable through the action of adjustment screw 86 which has spring 86a to take up its thread slack. Slide plate 84 may be locked in its adjusted position by means of lock bolt 87.

Thus the jewels may be adjusted vertically to the desired position between the grinding wheel and regulating roller.

Fig. IX illustrates the relative positional relation of the jewel support plate 8 and the jewel plunger 83. The plunger 83 is movable vertically with respect to the support plate 8 and is also so pivoted about horizontal pivot 88 as to permit arcuate adjustment of the plunger 83 with respect to the support plate 8.

The vertical movement of the plunger 83 is accomplished by adjustment of the auxiliary slide plate 85 with respect to the slide plate 84, in a recess of which it is mounted. This is done by releasing the locking screw 81 and moving plate 85 within the limits of its adjustment slot 92, under the heads of the shoulder screws 89 and 90, and the purpose of the adjustment is to per-

mit compensation for wear in support plate 9, or for adjustment to a particular jewel size.

The pivotal movement of the jewel plunger 83 is accomplished through the connection of the pivot plate 93 to the slide plate 85 through the pivot 88 and to the plunger sleeve 94 within which the plunger 83 is mounted. Lock bolt 95 is adapted to hold the pivot plate 93 in its adjusted arcuate position. The purpose of this arcuate adjustment is to provide means for centering the pin 10 with the jewels and with the upper edge of the support plate 9.

The jewel plunger 83 is slidable within and longitudinally of the sleeve 94 and when in operation, urges the pin 10 against the jewels under the action of spring 96 mounted within the sleeve 94. The action of spring 96 may be strengthened or weakened as desired through adjustment screw 97 which is held against the end 98 of the sleeve 94 by the spring 96, and the pin 10 may be held out of contact with the jewels when desired by positioning pin 99, which is secured to plunger 83, in retaining slot 100 formed in sleeve 94.

The jewel supporting structure which is particularly adapted to fine grinding of drilled jewels and which makes possible the forming of the jewel periphery to accurate concentricity with the jewel hole, is illustrated in Figs. X and XI.

The support plate 12 and the jewel wire 11 on which the jewels 8 are strung through their drilled holes, are secured to slide plate 101 and movable vertically therewith. Slide plate 101 is slidably mounted on pivot plate 79 and vertically adjustable through the action of micrometer screw 86. The slack of the thread of screw 86 is taken up by spring 86a and the slide plate 101 is held in adjusted position by lock screw 87.

Fixture plate 102 supports the jewel support plate 12 and the wire 11 and provides their connection to the slide plate 101 through assembly bolt 103.

The fixture plate 102 has an upright 104 which supports the wire holding member 105 (see Fig. XII) and an upright 106 which supports the wire tightening unit illustrated in Fig. XIII. The support plate 12 is adjustable with respect to the wire 11 through bolts 107 and openings 108 in the uprights 104 and 106.

The wire holder 105 (see Fig. XII) mounted in the upright 104 has an opening 109 through which the wire 11 is passed, and a slotted end 110 to which the wire is secured. The holder 105 is held in position by lock screw 111.

The wire drawing unit shown in Fig. XIII includes a bearing sleeve 112 mounted in upright 106 and adapted to be locked therein by set screw 113.

The sleeve 112 has an opening 114 through which the wire 11 passed, and is externally threaded at 115 with an adjustment nut 116 threaded thereon. A smaller sleeve 117, also externally threaded and hollow, extends within the opening 114 and an adjustment nut 118 is threaded thereon to move the sleeve 117 within the opening 114. Sleeve 117 has a slotted end 119 to which the wire 11 is secured.

The jewels 8 are threaded on the wire 11, one end of which is secured to the member 105 and the other to the sleeve 117. The nut 116 is so adjusted that the jewels are pressed end to end by wire holder 105 and sleeve 112 and the lock screws 111 and 113 are set. Then the nut 118 is turned to draw the wire 11 tight, and the jewels are ready for grinding.

The jewel holder unit of Figs. X and XI is pro-

vided with a handle 120, adapted, through a link arrangement like that of Fig. VIII, to move the unit horizontally toward or away from the grinding wheel. This arrangement may be used in this instance since the jewels are strung on wire 11 and will not fall when moved.

What I claim is:

1. In a grinding machine, a grinding wheel, a regulating roller adapted to rotate in cooperation with the grinding wheel, and a work support adapted to hold an object to be ground between the grinding wheel and the roller, said work support being mounted for pivotal movement with respect to said grinding wheel and said roller about a horizontal and a vertical pivot.
2. In a machine of the centerless grinder type, a grinding wheel, a regulating roller adapted to rotate in cooperation with the grinding wheel, a work support adapted to hold an object to be ground between the grinding wheel and the roller, and means for oscillating said grinding wheel along its own axis during the operation of said machine, said work support being mounted for pivotal movement with respect to said grinding wheel and said roller about a horizontal and a vertical pivot.
3. In a machine of the centerless grinder type, a grinding wheel, a regulating roller adapted to rotate in cooperation with the grinding wheel, a work support adapted to hold an object to be ground between the grinding wheel and the roller, and means for oscillating said grinding wheel along its own axis during the operation of said machine, said roller being mounted for movement toward and away from said grinding wheel about a horizontal and a vertical pivot, and said work support being mounted for pivotal movement with respect to said grinding wheel and said roller about a horizontal and a vertical pivot.
4. In a grinding machine, a grinding wheel, a regulating roller adapted to rotate in cooperation with the grinding wheel, and a work support adapted to hold an object to be ground between the grinding wheel and the roller, said roller being mounted for movement toward and away from said grinding wheel about a horizontal and a vertical pivot, and for such micrometrically adjustable vertical straight line movement as will enable said roller to move in an arc, about said horizontal pivot, of greater or less radius in accordance with said vertical adjustment.
5. In a grinding machine, a grinding wheel, a regulating roller adapted to rotate in cooperation with the grinding wheel, and a work support unit adapted to hold an object to be ground between the grinding wheel and the roller, said unit being mounted for pivotal movement with respect to said grinding wheel and said roller about a horizontal and a vertical pivot, and for micrometrically adjustable vertical straight line movement and comprising a base plate and a work holder, said holder being adjustable vertically and about a horizontal pivot independently of said base plate.
6. In a machine of the centerless grinder type, a grinding wheel, a regulating roller adapted to rotate in cooperation with the grinding wheel, a work support comprising a base plate and a horizontally acting spring pressed finger and being adapted to hold an object to be ground between the grinding wheel and the roller through vertical support by said base plate and endwise horizontal support by said spring finger, and means for oscillating said grinding wheel along its own axis during the operation of said machine.

7. In a machine for grinding drilled objects, a grinding wheel, a regulating roller adapted to rotate in cooperation with the grinding wheel, a work support comprising a base plate and a wire upon which said drilled objects are adapted to be threaded and held between the grinding wheel and the roller, means for applying tension end-wise of said wire, and means for oscillating said grinding wheel along its own axis during the operation of said machine.

8. In a grinding machine of the centerless grinder type, a base, a grinding wheel mounted on said base, an intermediate plate mounted on said base for sliding adjustment transversely of the working face of said grinding wheel, a pivot plate mounted on said intermediate plate and for movement with respect thereto about a vertical pivot, a slide plate mounted on said pivot plate for micrometrically variable sliding adjustment toward and away from said grinding wheel, an upright mounted on said slide plate for movement with respect thereto about a horizontal pivot, a regulating roller support mounted on said upright for micrometrically variable vertical sliding adjustment with respect thereto, a regulating roller mounted on said roller support and adapted to rotate in cooperation with said grinding wheel, and a work support adapted to hold an object to be ground between said grinding wheel and said roller.

9. In a machine of the centerless grinder type,

a grinding wheel, a resilient regulating roller rotating oppositely to and in cooperation with said grinding wheel, a work supporting unit arranged between the wheel and the roller, means for adjusting the roller relative to the grinding wheel, and means for adjusting the supporting unit vertically and about both a vertical and horizontal pivot.

10. In a machine of the centerless grinder type, a grinding wheel, a resilient regulating roller rotating oppositely and in cooperation with said grinding wheel, a jewel supporting unit arranged between said wheel and roller, jewels carried on said unit, and means for adjusting said supporting unit vertically and about a horizontal and vertical pivot to bring said jewels into contact with both grinding wheel and said resilient roller.

11. In a machine of the centerless grinder type, a grinding wheel, a resilient regulating roller rotating oppositely and in cooperation with said grinding wheel, a jewel supporting unit arranged between said wheel and roller, jewels carried on said unit, means for adjusting said supporting unit vertically and about a horizontal and vertical pivot to bring said jewels into contact with both grinding wheel and resilient roller, and means for moving said grinding wheel back and forth along its axis to present divergent grinding paths to said jewels.

ROBERT DANIEL HEFFELFINGER.
